Harry C. Schroeder ^{ATTORNEYS.}

UNITED STATES PATENT OFFICE

GEORGE H. ROBERTS, OF OAKLAND, CALIFORNIA

CLIPPER STERILIZER

Application filed April 4, 1931. Serial No. 527,691.

This invention is a clipper sterilizer, and has special reference to a device for sterilizing barbers' hair clippers.

The main object of the invention is to provide a device by means of which a barber's hair clipper may be quickly and conveniently sterilized.

Another object of the invention is to provide a device as outlined which is ready for instant use and which prevents escape of the sterilizing agents used and in which the sterilizing agent is conveniently added.

A further object of the invention is to provide such a device which is easily cleaned, attractive, economically manufactured, and which is efficient in its purpose.

Other objects and advantages of the invention will become apparent as the following description is read on the drawings forming a part of this specification and in which similar reference characters are used to designate similar parts throughout the several views, and in which:

Fig. 1 is a front elevation of the invention; 25 Fig. 2 is a side elevation thereof; and

Fig. 3 is a vertical longitudinal section through the invention showing a hair clipper in position for sterilization.

The body of the sterilizer consists of a cup 30 10 formed of sheet metal, the open end 11 of which is retracted to a smaller diameter as at 12 to slidably receive the cover or front 13 which is made of equal diameter to the body so as to provide a flush joint 14 when assembled. Engaging slots 15 are provided for rotatably securing the cover 13 by means of inwardly projecting pins 16 which are fixed on the inside of the cover flange 17.

A base 18 is fixed to the body as shown, 40 and has a flange 19 in which holes may be provided for securing the device in place. A receptacle 20 is placed within the body, the container being preferably filled with an absorbent material which is then saturated 45 with a volatile or slightly volatile antiseptic solution.

Secured to the inside of cover 13, by means of screws 21 which cooperate with a ring 22 of sheet metal, is a rubber diaphragm 23 which covers an opening 24 in the cover 13,

and which has an opening 25 therethrough slightly smaller than the body portion of the clipper 26 so as to seal about the clipper when inserted as indicated in Fig. 3.

A closure for opening 25 consists of a sheet 55 metal door 27 hinged at 28 and urged to closed position by a spring 29. A rubber pad 30 is secured to the front face of the door 27.

A clamp screw 31 is provided to secure the cover 13 against removal. 60

In normal position, the door 27 is resiliently retained in closed position against the diaphragm 23 closing the opening 25. The interior of the body is filled with the vapors of the antiseptic used. 65

Operation of the device merely requires forcing the clipper through the opening 25 in diaphragm 23 which tightly grips about the body of the clipper and seals against the escape of vapors. As the clipper is forced through the opening the cover 27 is forced back, permitting the vapors to reach all parts of the operating end of the clipper. After the required period of sterilization, the clipper is withdrawn, and the door 27 automatically closes, sealing the vapors within the body 10. 70 75

Having described an operative method of constructing and using the device, it will be understood that variations in construction 80 and arrangement which are consistent with the appended claims may be resorted to without detracting from the spirit or scope of the invention or sacrificing any of the advantages thereof. 85

I claim:

1. A clipper sterilizer comprising a vapor chamber, a removable cover therefor, an opening in said cover, a diaphragm over said opening and having a clipper receiving aperture adapted to contract about the body of said clipper, resiliently actuated means for closing said aperture, and a receptacle within said chamber for a volatile antiseptic. 90

2. A clipper sterilizer comprising a vapor chamber, a removable cover therefor, an opening in said cover, a diaphragm of elastic material fixed to the inside of said cover and extending over said opening, a restricted clipper receiving aperture in said diaphragm, 95

and resiliently actuated closing means for said aperture, and a receptacle for volatile antiseptic within said chamber.

3. A clipper sterilizer comprising a vapor chamber, a removable cover therefor, an opening in said cover, a diaphragm of elastic material fixed to the inside of said cover and extending over said opening, a restricted aperture through said diaphragm adapted to 10 expansibly receive the body portion of said clipper and engage thereabout to prevent the escape of vapors from said chamber, a spring actuated hinged door secured below said opening to the inside of said cover and 15 adapted to close said aperture, a resilient pad on said door, and a receptacle for a volatile antiseptic disposed in said chamber.

In testimony whereof I have affixed my signature.

20 GEORGE H. ROBERTS.
